UNITED STATES PATENT OFFICE.

CLARENCE A. WEIRICH, OF CANTON, OHIO.

WASHBOARD.

945,354.

Specification of Letters Patent.

Patented Jan. 4, 1910.

Application filed June 28, 1909. Serial No. 504,649.

To all whom it may concern.

Be it known that I, CLARENCE A. WEIRICH, a citizen of the United States, and a resident of Canton, in the county of Stark and State of Ohio, have invented certain new and useful Improvements in Washboards, of which the following is a full, clear, and exact specification.

My invention consists in certain novel 10 features of construction and of parts as will be hereinafter described and claimed.

In the drawing: Figure 1 is a perspective view of the washboard proper. Fig. 2 is a transverse section on line 1—1, Fig. 1. Fig. 15 3 is a view showing a portion of a plain sheet of metal and illustrating one of the side cuts in the sheet. Fig. 4 is a similar view, showing the sheet folded or lapped at the adjacent edges of the cut.

20 Similar numerals of reference indicate corresponding parts in all the figures of the drawing.

In the accompanying drawing, 1 represents the sheet of metal which is cut, 25 stamped and rolled to constitute a rubbing surface and a shelf or ledge, top and leg holding tubes. For the purpose of providing means for properly stamping the sheet to produce the lateral flange or shelf 2, the 30 vertical edges of the sheet 1 are cut as at 3, and the sheet of metal crimped, whereby the lateral flange 2 is formed. In so forming the ledge 2 the portions of the sheet adjacent the cut 3 are lapped for a short distance, 35 one upon the other as illustrated at 4, Fig. 3. The sheet is provided with the integral tubes or cylindrical rolls or beads 5, which tubes or cylindrical rolls are for the double purpose of giving rigidity to the washboard 40 proper and at the same time providing means for connecting the legs 6 to the sheet constituting the washboard proper. It will be understood that by my peculiar arrangement I am enabled to produce a washboard 45 from a single sheet of metal having the rubbing surface and also the necessary flange or shelf.

For the purpose of presenting a stiff or rigid rubbing surface, the rubbing surface is formed convex as illustrated in Fig. 2. 50 The legs 6 are inserted in the tubes or cylindrical rolls or beads 5 as illustrated in Fig. 2 and held in proper relationship therewith by means of the nails 7 or their equivalents.

In forming a finished washboard from a 55 plain sheet of metal substantially the following method is carried out: First, the sheet is cut and sized, second cutting slits in the edges of the sheet, third stamping the board, and fourth forming the tubes upon 60 the vertical edges upon the board. However, I do not desire to be confined to the exact method as just above pointed out as it will be understood it may be varied without departing from my invention. 65

It will be understood that in order to provide a finished board the metal should be galvanized after it is formed, thereby closing the slits and producing a water-tight sheet throughout its entire surface 70 and providing a water-tight shelf at the top of the board.

Having fully described my invention what I claim as new and desire to secure by Letters Patent, is— 75

A washboard formed of a single sheet of metal having its vertical edges slitted, a shelf formed intermediate the top and bottom ends of the sheet of metal, a roughened rubbing portion located below the shelf, 80 said rubbing surface formed convex and integral cylindrical rolls or beads located upon vertical edges of the sheet, substantially as and for the purpose specified.

In testimony that I claim the above, I 85 have hereunto subscribed my name in the presence of two witnesses.

CLARENCE A. WEIRICH.

Witnesses:

SYLVIA BORON,
F. W. BOND.
